DESIGN FOR A RUG.

SPECIFICATION forming part of Design No. 16,165, dated July 14, 1885.

Application filed June 12, 1885. Term of patent 3½ years.

To all whom it may concern:

Be it known that I, RICHARD PAUL HEMMING, a citizen of the United States, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such person to use my invention.

The leading features of my design consist in a center panel showing a ground of floral ornamentation, with two geranium leaves of variegated colors. The center panel is surrounded by an ornamental border. At each corner and on the sides is shown a geranium leaf. The center panel is surrounded by an

outer panel showing a floral ground and a geranium leaf at each end of the panel. The whole is surrounded by an ornamental border, as shown in the photographic print accompanying this specification.

The photographic print illustrates and represents one half of the design or rug. The other half, described but not shown, is exactly like it.

What I claim as my invention is—

The design for a rug, consisting of an outer and inner panel showing grounds of floral ornamentation, ornamental borders, and geranium leaves, as shown and described.

R. PAUL HEMMING.
